UNITED STATES PATENT OFFICE.

MORTON DECKER, OF CHICAGO, ILLINOIS, AND CHARLES H. SHAW,
OF MILWAUKEE, WISCONSIN.

CENTRIFUGAL LIQUID-SEPARATOR.

No. 857,794.

Specification of Letters Patent.

Patented June 25, 1907.

Application filed December 3, 1906. Serial No. 346,075.

To all whom it may concern:

Be it known that we, MORTON DECKER, a citizen of the United States, residing at Chicago, in the county of Cook and State of Illinois, and CHARLES H. SHAW, a citizen of the United States, residing at Milwaukee, in the county of Milwaukee and State of Wisconsin, have invented certain new and useful Improvements in Centrifugal Liquid-Separators, of which the following is a specification, reference being had to the accompanying drawings.

Our invention relates to centrifugal liquid separators, and particularly to separators adapted to separate cream from milk.

The chief object of our invention is to provide a new and improved centrifugal separator which will effect a thorough and practically entire separation of the cream from the blue or skinned milk readily, economically and rapidly, and which is of effective and simple construction.

Another object of our invention is to provide a new and improved connecting spindle between the driving mechanism of the separator and the bowl which receives the milk.

Another object of our invention relates to a new and improved accelerator located within the bowl, which is adapted to effect the first separation of the cream from the milk, and also to accelerate the rotary movement of the milk after its first separation to the speed of the bowl.

Another object of our invention is to provide new and improved liners for such separators, which are adapted to readily and surely effect the final and complete separation of the cream from the blue or skinned milk.

Other objects of our invention are to improve such separators in sundry details hereinafter pointed out.

In the drawings,—Figure 1 is a vertical section of the machine; Fig. 2 is an enlarged detail of the bowl, showing the bowl in central vertical section on line 2—2 of Fig. 5; Fig. 3 is an enlarged detail of the bowl and upper end of spindle, showing the bowl in vertical section on line 3—3 of Fig. 5; Fig. 4 is an enlarged detail, being a vertical elevation of the central standard with its upper end in ver-

tical section; Fig. 5 is a top or plan view of the central standard shown in Fig. 4; Fig. 6 is an enlarged detail, being a top or plan view of one of the disk-liners; Fig. 7 is an enlarged detail, being a vertical section of one of the disk-liners upon line 7—7 of Fig. 6; Fig. 8 is an enlarged detail, being a vertical section of the accelerator on line 8—8 of Fig. 9; Fig. 9 is an enlarged detail, being a top or plan view of the accelerator; and Fig. 10 is an enlarged detail, being a cross-section on line 10—10 of Fig. 3.

Referring to the drawings,—11 is a standard, which is hollow, as is best shown in Fig. 1, to contain parts of the driving mechanism and rests upon a base 12.

13 indicates a sprocket-wheel, which is mounted upon a shaft 14 journaled in the standard 11 and adapted to be driven by a crank, or any other suitable means (not shown).

15 indicates a smaller sprocket-wheel mounted upon a shaft 16 which is journaled in the standard 11.

16 indicates a sprocket-chain connecting sprocket-wheels 13 and 14.

17 indicates a gear, which is keyed, or otherwise secured, upon the shaft 16 and meshes with a pinion 18 keyed, or otherwise secured, to a shaft 19 which is journaled in the standard 11.

20 indicates a toothed wheel keyed, or otherwise secured, to the shaft 19.

21 indicates a spindle, the lower end of which rests in a bearing 22 in the standard 11.

23 indicates a worm on the spindle 21 adapted to be engaged by the teeth upon the wheel 20.

24 indicates a cylindrical casing, which is secured to the standard 11 and is adapted to contain and support the rotating parts and other parts hereinafter described. As is best shown in Fig. 1, it is in the form of a hollow cylinder open at the top and whose interior is circular in cross-section.

25 indicates a bearing, which is mounted in a suitable opening in the bottom of the casing 24, and in which the upper end of the spindle 21 is journaled.

26 indicates a collar on the spindle 21, preferably integral therewith. The collar 26 is

small enough to pass through the opening in the bottom of the casing 24, which supports the bearing 25, but is, of course, larger than the opening in the bearing 25, in which the 5 spindle 21 is journaled, and is located immediately below the lower end of said bearing to resist any upward thrust on the spindle 21. The upper end of the spindle 21, as is best shown in Figs. 2 and 3, is provided with a tapered opening in which a tapered spindle of the bowl hereinafter described rests, and is also provided at its upper end, as is best shown in Fig. 2, with a slot 27 which extends downward and thence laterally to afford a 10 bearing for a pin on the spindle of the bowl hereinafter described.

28 indicates the bowl, which is cylindrical in shape and whose hollow interior is circular in cross-section, and consists of a side 29, bottom 30 and top 31, as is best shown in Figs. 1, 2 and 3. As is best shown in the same figures, the side portion 29 rests within upturned flanges of the bowl 28. The top 31 is provided with a peripheral flange 32, which is 15 adapted to rest upon the top of the side 29, and with an interior annular projection 33, which is adapted to rest and fit closely within the side 29. The top 31 is in the shape of a frustum of a cone, sloping upward and inward to a head 34. The bottom of the bowl 28 is provided with a central stud 36, which is 20 provided with a central opening or cavity circular in cross-section and screw-threaded at its top.

36 indicates a standard, which is in the form of a tube having an expanded cone-shaped base 37 and provided with a series of radial wings 38. One of these wings 38 is provided with a longitudinal centering edge 39 adapted to engage a corresponding notch in the disks hereinafter described. The lower conical-shaped end of the standard 36 rests upon the bottom 30 of the bowl 28, and is of such a size as to extend completely 45 across the bottom against a suitable annular ridge 40 formed on said bottom. The upper tubular portion of the standard extends upward nearly to the top of the bowl, as is best shown in Figs. 1, 2 and 3. The cone-shaped portion 37 of the standard is provided with 50 two series of openings 41—42, as is best shown in Figs. 3 and 5. The openings 41 are arranged upon an inner circle and openings 42 upon an outer circle on the cone-shaped portion 37, and are arranged in pairs so that one opening 41 and one opening 42 shall be 55 on the same radius of the circle, as is best shown in Figs. 4 and 5. The openings 41 are, therefore, nearer the center and higher 60 on the cone than the openings 42.

43 indicates an accelerator of circular cross-section, somewhat smaller than the interior of the cone 37 and shown in detail in Fig. 8 and 9, and also in section and in po-

sition in Figs. 2 and 3. This accelerator is 65 what may be called "bell shaped." Its upper portion 44 is cylindrical and from thence the accelerator slopes downward and outward, being curved toward its lower edge. The upper edge of the accelerator is beveled 70 to rest snugly and liquid-tight against the under surface of the cone 37 and is of such diameter that the beveled upper edge resting against the under side of the cone comes between the openings 41 and the openings 42 75 so as to separate them from each other. The shape of the inside cavity of the accelerator 43 corresponds to that of its outside, as is best shown in the sectional views of Figs. 2, 3 and 8.

43^a indicates openings, preferably four in number, and preferably in the form of semi-circular notches in the bottom of the accelerator 43 and leading into the chamber formed between the exterior of the accelerator 43 and the conical chamber formed by the bottom of the central standard 36. The upright portion 44 of the accelerator is provided with a series of openings 43^b, preferably four in number, and located between the wings 45. Upon its upper surface the accelerator 43 is provided with a plurality of wings 45, preferably four in number, and extending downward over its upper surface a short distance above the bottom of the separator. The upper surface of these wings is 80 designed to bear closely against the under side of the cone 37.

47 indicates a milk-tube, which is adapted to pass through the head 34 of the top 31 and whose lower end is screw-threaded to engage the screw-threaded opening in the stud 35. The upper end of the tube 47 is provided with a circumferential shoulder 48 which is adapted to bear upon the top of the head 34 90 to-lock the parts in position when put together, as hereinafter described.

49 indicates a plurality of openings through the stud 35. These openings slope slightly upward from the interior to the exterior in order to direct the milk, as hereinafter described.

50 indicates a slot, which passes upward into the head 34 and whose inner surface is open. It is closed, however, when the parts are together, by the exterior of the standard 36, as is best shown in Figs. 2 and 10. At its top this opening 50 communicates with a suitable opening at right angles to it in the head 34 into which is inserted a tube 51, which is screwed into said opening by means of suitable screw-threads, and whose position may be thereby adjusted to expose more or less of the slot 50.

52 indicates a plurality of tubes, preferably four in number, which are secured on the inside of the cover 31. These tubes 52 at their lower end open into openings 53 in

the annular projection 33 and at their upper ends into tubular openings 54 through the head 34.

55 indicates a plurality of disk-liners for the bowl of the accelerator. As is best shown in Figs. 6 and 7, these disks or disk liners are curved into the shape of a portion somewhat less than half of a sphere and are formed of thin metal. Each of these disks 55 is provided at its lower edge with a horizontal flange 56 and is provided with a central opening through which the tubular portion of the standard 36 extends when in position, as is best shown in Figs. 6 and 7. This opening is 15 provided with a plurality of notches 57, which are adapted to fit closely over the wings 38 on the standard 36, and one of them is provided with a smaller notch 58 which engages the narrow edge 39 for the purpose of 20 centering the disks in proper position. The central opening of the disks is also provided with a plurality of radial extensions 58 which are preferably star-pointed—that is to say, wider at their inner ends and narrowing gradually to a rounded point at the outer. 25 These radial openings 58 are the same in number as the openings 42 and register with them so that when the disks are in place the openings in each of these disks will lie above and 30 register with the openings 42 to afford a free passage upward of the milk, as hereinafter described. Each of the disks 55 is provided upon its upper surface with a stud or projection 59 which serves to separate it suitably from the disk immediately above it. The 35 disks, as has been said are curved and are so shaped that when placed in position, one upon the other, the space between them will gradually narrow from the upper and central portion toward the edge of the disk between the flanges 56, and they are so shaped and spaced that the space between the flanges 56 is the same as the space between the disks at the central opening.

40 60 indicates a tapered spindle formed upon the bottom 30 of the bowl 28 and adapted to rest snugly within the tapered recess in the top of the spindle 21.

45 61 indicates a pin projecting from the spindle 60 near its upper end and adapted to engage the slot 27.

50 Referring to Fig. 1, 62 indicates a vessel having a cone-shaped bottom 63 adapted to rest upon the top of the casing 24. The cone-shaped bottom is provided with suitable flanges 64 and 65 adapted to rest, respectively, upon the top of the casing 24 and against the inside of the top of the casing to secure the vessel 62 in place. The conical 55 bottom of the casing 63 is provided with an opening of suitable size to receive snugly within it the head 34 of the top of the bowl and encircles said top just below the screw-tube 51. 66 indicates a second cylindrical

vessel, which is provided with a sloping and 65 slightly cone-shaped bottom 67 which is adapted to rest within the upper edge of the vessel 62. The bottom 67 is provided with a circular opening into which the upper portion of the head 34 of the bowl snugly rests and 70 the edge of the opening just engages the surface of the head above the screw-tube 51. 68 indicates a vessel which rests within the upper portion of the vessel 66. The bottom of the vessel 68 is provided with an opening 75 within which rests the spindle 70 of a float 71. The edges of the opening are formed or pressed to form a short tube that will enter into the upper end of the milk tube 48. 72 indicates a tube, which leads out from the vessel 80 62, and 73 a tube which leads out from the vessel 66.

The parts are put together as follows: The accelerator 43 is first placed in position on the bottom of the bowl, the top 31, of course, being removed. The central tubular standard 36 is then placed in position in the bowl. The several disks or disk liners are then placed in position, one above the other, until the requisite number are inserted. The top 31 of 85 the bowl is then placed in position, the annular shoulder 33 pressing against the flange of the top disk and forcing all the parts into position. The milk-tube 47 is then inserted and screwed home. The shoulder 48 bearing upon the head 34 will force the top 31 downward into position, forcing the disks close together and by the pressure of the lowest disk upon the lower portion of the conical part 37 of the central standard 36 90 will lock all the parts securely together. The bowl is then placed in position in the casing, the taper spindle 60 entering the spindle 21 and the pin 61 engaging the slot 67. The several vessels are then placed in position, 95 one above the other, as described, and the device is ready for operation.

The operation of the above-described machine is as follows: The machine being set into operation, whereby the bowl is rotated 100 at a very high speed, milk is poured into the vessel 68, which is kept filled with a constant supply. The milk passes down the milk-tube 47 and emerges through the openings 49 at the bottom and, of course, is set in rotation 105 as it emerges. The slight upward slope of the openings 49 throws the milk against the under surface of the accelerator 43, and being rotated rapidly the centrifugal force operates to separate the milk from the cream to a large 110 degree. The heavier milk with still a portion of cream remaining in it is thrown outward and passes out through passages 43^a, while the lighter cream, rising along the interior surface of the accelerator 43, passes 115 upward through the openings 41 from whence it rises along the exterior of the central standard 36 to the top of the bowl to beulti- 120 125

mately discharged through the passage 50, as hereinafter described. It is found that this part of the process removes about forty per cent. of the cream. The milk containing the other sixty per cent. of cream passes through the chamber between the under side of the conical portion 37 of the upright standard 36 and the exterior of the accelerator, where, by the operation of the wings 45, it rotates with the full speed of the bowl. This effects a still further separation of the milk and cream by the operation of centrifugal force. The heavier milk with still a small portion of the cream hugging the interior surface of the conical portion 37 of the standard 36 passes upward and out through the openings 42. The cream of lesser specific gravity flows upward along the exterior surface of the accelerator, and passing inward through the openings 43^b, joining the upward-flowing stream of cream separated from the milk inside of the accelerator, passes with it upward through the openings 41. The milk freed from most of the cream passing upward through the openings 42 into the bowl passes upward through the star-pointed radial openings 58 in the several disks, which, it has been said, register with the openings 41—42. As has been said, the cream which has been theretofore freed from the milk rises in the bowl hugging the tubular portion of the central standard 36. The milk freed of almost all the cream is thrown outward by centrifugal force into the spaces between the disks 55 and flows downward so as to fill those spaces. On account of the spaces between the disks narrowing to a very narrow opening at their edges, the milk with the small percentage of cream still remaining in it is still further separated,— the thin blue milk spreading outward passes from the narrow spaces between the edges of the disks while the cream separated by centrifugal force from the milk rises along the upper surface of each disk, forced back by the constantly inflowing stream of milk until it meets the ascending stream of cream previously separated, as above described. The milk, thus practically completely freed from the cream, issues between the edges of the disks and is directed by the flanges upon the disks outward so that it readily flows upward and does not by being forced downward, as would be the case if the flanges were not there, tend to resist the upward flow of skimmed milk. The stream of cream thus flowing upward, as above described, near the central portion of the bowl around the tubular portion of the standard 36 all passes upward through the tube 50, out through the screw-tube 51, into the vessel 62, from which it is drawn out into a suitable receptacle through the tube 72. The skimmed or blue milk thrown by centrifugal force to the exterior of the bowl passes upward through the tubes 52 and tubu-

lar openings 54 into the vessel 66, from which it is drawn off through the spout 73 into any suitable receptacle.

By reason of the construction of the spindle 21, which is in a single piece and is journaled in the removable bearing 25, together with the tapered spindle 60 on the bottom of the bowl and the engaging slot and pin, it will be seen that a structure is obtained which has only two bearings for the shaft 21 and at the same time is capable of being readily and easily taken apart. The shoulder 26 on the spindle 21 holds the shaft against upward thrust. It will be seen thus that the bowl is easily and readily removable for cleansing and repairing the various parts, and by the removing of the removable bearing 25 the spindle itself may be easily and readily removed whenever it is desired to do so.

That which I claim as my invention and desire to secure by Letters Patent is,—

1. In a centrifugal cream-separator, the combination with a bowl, a milk-tube, a conical chamber surrounding the lower end of said milk-tube and provided with two series of annularly-disposed openings, of a substantially bell-shaped accelerator located within said conical chamber and provided with milk discharge openings at its lower edge, cream passages near its upper portion, and accelerating devices on its outer surface.

2. In a centrifugal cream-separator, the combination with a bowl, a milk-tube, a conical chamber surrounding the lower end of said milk-tube and provided with two series of annularly-disposed openings, of a substantially bell-shaped accelerator whose upper edge engages the inner surface of said conical chamber between said two series of openings and whose lower edge rests upon the bottom of the bowl, said accelerator being provided with milk discharge openings at its lower edge, cream passages near its upper portion, and accelerating devices on its outer surface.

3. In a centrifugal cream separator, the combination with a bowl, a milk tube, and a conical chamber surrounding the lower end of said milk tube and provided with a plurality of annularly-disposed openings, of a substantially bell-shaped accelerator located within said conical chamber and provided with milk discharge openings at its lower edge, cream passages near its upper portion, and accelerating devices on its outer surface, and a plurality of liner plates each provided with a central opening adapted to embrace said milk tube and having a plurality of radial extensions to said central opening registering with the openings of said conical chamber.

4. In a centrifugal cream separator, the combination with a bowl, a milk tube, and a conical chamber surrounding the lower end of said milk tube and provided with a plural-

ity of radially-disposed pairs of openings, of a substantially bell-shaped accelerator located within said conical chamber and provided with milk discharge openings at its lower edge, cream passages near its upper portion, and accelerating devices on its outer surface, and a plurality of liner plates each having a central opening adapted to embrace said milk tube and a plurality of radial extensions

of said central opening each registering with one pair of the radially-disposed pairs of openings in said conical chamber.
